UNITED STATES PATENT OFFICE.

MORDICA M. STEWART AND JOHN D. M. RUSSELL, OF MAYFIELD, KY.

IMPROVEMENT IN EXCAVATING AND DITCHING MACHINES.

Specification forming part of Letters Patent No. 123,303, dated January 30, 1872.

To all whom it may concern:

Be it known that we, MORDICA M. STEWART and J. D. M. RUSSELL, of Mayfield, in the county of Graves and State of Kentucky, have invented a new and valuable Improvement in Ditchers; and we do hereby declare that the following is a full, clear, and exact description of the construction and operation of the same, reference being had to the annexed drawing making a part of this specification and to the letters and figures of reference marked thereon.

Figure 1 of the drawing is a representation of a vertical longitudinal section of our invention. Fig. 2 is a top-plan view of the same.

This invention has relation to ditching-machines or excavators; and the novelty consists in the construction and adjustable arrangement of the cutters and scraper, as hereinafter described.

Referring to the drawing, A represents the main frame of my improved ditching-machine mounted at its forward end on the wheels B B' supported by the axle C. Secured to the inner face of the wheel B' is a spur-wheel, D, which engages with a similar wheel, D¹, on the end of a transverse shaft, D², which holds a grooved pulley-wheel, D³. E indicates a transverse bar, which is supported upon brackets e projecting from the axle C, and is armed with a number of depending cutters or plows, F F', which are designed to dig into the earth in order to form the ditch. The brackets e have loops or collars on their outer ends which encircle the bar E and allow it freedom to turn.

The cutters F', it will be noticed, project toward the sides of the machine obliquely, their points falling behind the edges or peripheries of the wheels B B'. The cutters may be adjusted to sink different depths by means of the levers G, which are attached to the bar E and pivoted to the rods H. I designates the scraper, concave or shovel-shaped, as shown, its lower part being inclined toward the points of the plows. The scraper has oblique beveled sides i, which are hinged to the rods H, thus rendering the scraper adjustable simultaneously with the plows. The back part of the scraper is hinged to the frame A. O designates a caster-wheel attached to the rear end of the ditcher.

The number of plows to be used with this ditcher should be about nine.

By removing the middle plow and separating the scraper from the frame the machine may be used as a corn or cotton cultivator.

We claim as our invention—

1. In a ditching-machine or excavator, we claim the combination of the adjustable plows F F', levers G, rod H, and hinged scraper I, as and for the purpose specified.

2. In a ditching-machine, the arrangement of the plows or cutters F', as described.

In testimony that we claim the above we have hereunto subscribed our names in the presence of two witnesses.

MORDICA M. STEWART.

JOHN DAVID M. RUSSELL.
